ADJUSTABLE DIE AND BLADE FOR THE
SAME

Merle E. Halstead, Owego, N. Y.

Application July 10, 1935, Serial No. 30,646

20 Claims. (Cl. 164—31)

This invention relates to adjustable dies for cutting different size elements of leather, cloth or other material, and to cutter blades for such dies.

5 In its broader aspect the invention is applicable to apparatus for cutting blanks for the manufacture of pocket books, key cases and other articles, or cutting fancy edges thereon; but the invention is intended more particularly for pinking the edges of the blanks used for vamps, quarters, or other elements of shoe uppers.

In the manufacture of shoes, the different elements are cut out as blanks with smooth edges and if the style of shoe to be made is one which is 15 decorated by pinking edges, the element is placed in a die which cuts the edge to the desired pattern. Each style of shoe must be made in a number of sizes, and when the elements are graded it is necessary to have as many pinking dies as there are sizes of shoes to be made. Aside 20 from the inconvenience and loss of time entailed in changing dies, the necessity for a different die for each size of shoe of each particular style makes the manufacturer's investment in dies very substantial.

25 It is an object of this invention to provide an improved die which is adjustable to cut elements of different sizes. It is a more particular object of the invention to provide an adjustable die for pinking the edges of elements of shoe uppers which are graded for shoes of different size.

Another object of the invention is to provide an improved pinking blade of great flexibility which will conform to abrupt curves and which 35 can have its contour readily changed to shift a curve of short radius to another part of the blade.

Other objects, features, and advantages of the 40 invention will appear or be pointed out as the specification proceeds.

In the drawings—

Fig. 1 is a top plan view of an adjustable die embodying the invention;

Fig. 2 is a view similar to Fig. 1 but showing 45 the die adjusted for pinking vamps of larger size;

Fig. 3 is an enlarged plan view of the adjustable die of Figs. 1 and 2 with the stripper plates, guides and center cover plate removed, and one of the central sliding plates broken away to show 50 the cam means beneath.

Figs. 4—9 are fragmentary sectional views taken 55 on the line 4—4 to 9—9, respectively, of Fig. 3, but with the stripper plates, guides and cover plate in position, and a vamp against the guides in some of the views.

Fig. 10 is a perspective view of the pinking blade.

In Fig. 1 the die is adjusted for pinking the smallest size of vamp. The vamp edge includes a center portion "c" which may be straight or slightly curved, and on either side of the center portion a curve of radius "r", which is followed by a straight section "l", after which the edge curves outward with a radius "R".

Vamps of larger size include a longer center 10 portion, as indicated at "C" in Fig. 2, the same curve of radius "r", followed by a longer straight section "L" and then curve outward with the same radius "R" as in Fig. 1. In order to compare the contour of the vamp edge which the machine is adjusted to cut in Fig. 2 with the vamp 15 cut in Fig. 1, the outline of the larger vamp is indicated by the dotted line "V" in Fig. 1.

A pinking blade 13 is held to the contour shown 20 in Fig. 1 by supporting means which will be described. From a comparison of the blade contour of Fig. 1 with the outline "V" of the larger vamp edge it will be observed that in changing 25 the contour of the pinking blade from that shown in Fig. 1 to that shown in Fig. 2, the center portion "c" must not only lengthen, but move down; the curve with the radius "r" must be located both lower and further to the right, with the result that a different part of the blade is bent 30 to this radius; the section "l" must be increased in length and moved to the right; and the curved section with radius "R" must be shifted to the right.

The blade 13 is sufficiently flexible so that any 35 portion of it can be bent around sharp right angle turns, or arcs of short radius, and straightened again as the holder is adjusted, without any injury to the blade. This high degree of flexibility is obtained by making the blade of metal between .005 and .015 inch thick, but in the elevation views 40 of the drawings this thickness has been exaggerated for greater clearness.

The blade is corrugated to give the cutting edge the form desired for the pinking. In the blade illustrated the corrugations are pointed at both 45 sides of the blade to form a zig-zag cutting edge. The corrugations extend for the full height of the blade to insure maximum flexibility.

One or both edges of the blade 13 may be 50 sharpened, but the blade is so thin that it can be used for cutting even though it has not been sharpened. When the edge is to be made sharp, this is done while the blade is a flat metal strip and before it is corrugated.

Because of the extreme thinness of the blade 55

13 it is necessary that it have full lateral support to hold it to the desired contour and to prevent it from collapsing or bending over when subjected to the cutting pressure.

5 When on the die, the vamp rests on stripper plates 14, 15 and cover plate 17. This cover plate is supported by the inner edge portion of the stripper plates, these edge portions being depressed by an amount equal to the thickness of 10 the center cover plate so that the top surfaces of all of these plates are flush. A spring 18 riveted to the center cover plate extends under the edges of the stripper plates to retain the cover plate in position.

15 The edge of the uncut vamp abuts against end guides 19 and 20 which are curved to the radius "R". There is no vamp on the die in Figs. 1 and 2, but Fig. 8 shows the edge of a vamp 22 supported on the stripper plate 14 and in abutment with the end guide 19. Center guides 24 and 25 (Figs. 1 and 2) contact with the edge along the throat of the vamp. In Fig. 6 the vamp 22 is shown abutting against the center guides 24 and 25.

25 The end guides 19 and 20 contact with straight edges 27 and 28 of the center guides 24 and 25 respectively, and these straight edges are tangent to the curved faces of the end guides at the pointed lower edges of the end guides 19 and 20. 30 During adjustment of the die, the center guides 24 and 25 move in the direction that the edges 27 and 28 extend, while also moving sideways at the same rate as the end guides 19 and 20. The center guides and end guides always meet 35 therefore along the lines 27 and 28.

The pinking blade 13 is held to the contour of the guides 19, 20, 24 and 25 so that when these guides are adjusted to contact with the edge of any particular size of vamp, the blade is in position 40 to pink the edges of the vamp. The guides 24, 25, 19, 20, and stripper plates 14, 15 are supported by springs 30, but the pinking blade 13 is unyieldingly supported by plates resting solidly on the base of the die.

45 When the top block 31 (Fig. 4) of the die forces the vamp 22 downward, the springs supporting the guides and stripper plates yield and the vamp is pressed against the top edge of the pinking blade 13. Paper 32 over the bottom face of the 50 block 31 prevents the edge of the blade from coming against the hard face of the block.

The springs 30 are held in position by studs 33 which extend downward from the under sides of the end guides 19 and 20, the center guides 55 24 and 25, and the stripper plates 14 and 15.

Fig. 3 shows the adjustable die of Figs. 1 and 2 with the guides, stripper plates and cover plate removed. The center portion of the pinking blade 13 extends through a clamp 35 which is 60 connected to a slide 36 by screws 37. The bottom edge of the pinking blade 13 rests on the slide 36, as shown in Fig. 4, and the blade is held in the clamp 35 by a block 38 which fits into a recess having a sloping back wall 49 which causes 65 the block 38 to wedge against the blade 13 as the block is moved downward in the recess by a screw 41 which threads into the slide 36.

The slide 36 rests on a base 43 and is confined against lateral movement on the base by guide 70 plates 45 and 46. A nut 47 (Fig. 4) is connected to one end of the slide 36 and is a running fit in a slot 48 in the base 43. The forward end of the slot 48 is closed by a block 50 attached to the base as a rigid part thereof. A lead screw 75 51 threads through the nut 47 and is journaled

in the base 43 and block 50 at opposite ends of the slot 48.

The unthreaded stem portion at the forward end of the lead screw 51 has a handle 53 freely 5 slideable between a head of the lead screw and a collar 55 pinned on the stem portion in position to bear against the front face of the block 50. A tongue 56 on the handle 53 fits into a groove in the collar 55 to operatively connect the handle 53 with the lead screw 51. The handle can 10 slide far enough on the stem portion of the lead screw to disengage the tongue from the groove so that no matter what angular position the lead screw may be in when the die reaches the desired adjustment, the handle 53 can be disengaged from the collar 55 and put into a horizontal position.

Under the end guides 19 and 20 of Figs. 1 and 2, there are end clamping plates 59 and 60 (Fig. 4) which have the same shape as the respective 20 end guides under which they are located. Center clamping plates 64 and 65 have the same shape as, and are located under, the center guides 24 and 25 of Fig. 1. Each of the guides moves laterally as a unit with its underlying clamping 25 plate.

Referring to Fig. 3, clamping plates 59 and 64 rest on a supporting plate 67, which slides on the base 43 between undercut bearing plates 69. Fig. 9 shows the stepped end of the supporting 30 plate 67 and its relation to the bearing plate 69.

Referring again to Fig. 3, the clamping plates 60 and 65 rest on a supporting plate 70 which slides on the base 43 between the undercut bearing plates 69. The top surfaces of the supporting 35 plates 67 and 70 are flush with the upper faces of the guide plates 45 and 46, and the portions of the pinking blade beyond the plates 45 and 46 rest on the supporting plates 67 and 70.

The means for moving the supporting plates 40 67 and 70 toward and from one another is shown in Figs. 3 and 6. A cross piece 72 is secured to the slide 36 and carries studs 73 which extend into diagonal slots 74 in the supporting plates 67 and 70. When the handle 53 is operated to move the slide 36, the studs 73 move along paths parallel to that of the slide 36 and cooperate with the side walls of the diagonal slots 74 with a cam action to cause the supporting plates 67 and 70 to move toward or away from one another 45 depending upon the direction of movement of the slide 36. The clamping plates 59 and 64 move with the supporting plate 67, and the clamping plates 60 and 65 move with the supporting plate 70.

In addition to their movement toward and from one another with the supporting plates 67 and 70, it is also necessary for the center clamping plates 64 and 65 to move parallel to their straight edges 27 and 28.

The clamping plate 65 is held on the supporting plate 70 by an undercut guide 76 which is fastened to the supporting plate 70 by screws, as shown in Figs. 3 and 7. This guide 76 extends parallel to the edge 28 and fits in a slot 77 in the clamping plate so that the only movement which the clamping plate can make with respect to its supporting plate 70 is a movement parallel to the edge 28. Such movement is imparted to the clamping plate 65 by the cross piece 72 which fits a slot 78 in the clamping plate 70.

The connection of the clamping plate 64 to its supporting plate 67, and the means for moving 75

this clamping plate are the same as for the clamping plate 65 described above.

The pinking blade 13 is held against the clamping plates 60 and 65 by a spring 80. This spring has one end hooked around a stud 81 which is screwed into the supporting plate 70. A kinked portion of the spring extends around a stud 82 which is also screwed into the supporting plate. The free end of the spring 80 presses against the stud 81 and tends to rotate the inner portion of the spring about the stud 82 as a center. This pressure causes the spring to assume the contour indicated by dotted lines in Fig. 3.

The space between the spring 80 and the clamping plates 60 and 65 comprises a channel in which the pinking blade slides when the die is being adjusted for a different size of vamp. After adjusting the die the width of this channel is reduced by pressing the spring 80 against the pinking blade to clamp the blade firmly between the spring and clamping plates. The faces of these parts which clamp the blade in position are sufficiently high to give the blade the necessary lateral support to prevent it from tipping during the cutting operation.

The pinking blade over the supporting plate 67 is confined between the clamping plates 59 and 64 and a spring 84 which is similar to the spring 80. A yoke 85 contacts with both the springs 80 and 84 to hold them in clamping position, as shown in Fig. 3. The yoke 85 is connected to a lever 87 by a cylindrical bearing which permits the yoke to equalize the pressure of the springs 80 and 84. The lever 87 has a fulcrum 83 which is fixed with respect to the base 43.

A cam 90 is rotated by a handle 91 about a fixed axis 92. This cam moves the lever 87 to clamp the springs 80 and 84 against the pinking blade. When the cam is in position to clamp the blade, the cam-operating handle 91 is above the slide-operating handle 53 so that the latter cannot be turned to change the adjustment of the die when the pinking blade is not free to slide lengthwise in the channel.

In clamping the pinking blade 13 against the sides of the clamping plates 64 and 65, the springs 80 and 84 draw the blade firmly against the curved end faces of these clamping plates so that even the short sections of blade between the springs and the clamp 35 have a substantial amount of lateral support.

Figs. 3 and 9 show an indicator 94 which has a pivot connection 95 with the supporting plate 67. A pin 96 extends upward from the base 43 through a slot in the plate 67 and into a bifurcated end of the indicator 94. As the supporting plate 67 moves on the base 43, the relative movement of the pin 96 and the indicator 94 causes the indicator to turn about its pivot connection 95 so that one end of the indicator sweeps across a scale on the plate 67. This scale can be used to designate the size of vamp for which the die is adjusted.

It will be apparent that this invention is not limited to the particular embodiment which has been illustrated and described, and that features of the invention can be used without others.

I claim:

1. An adjustable die comprising clamping means forming a channel for a flexible cutter blade, means for changing the contour of the channel, and releasable resilient means tending to reduce the width of said channel so that a blade in the channel is held firmly by said clamping means.

2. An adjustable die including a channel for supporting a flexible cutter blade, said channel extending for substantially the entire length of the cut, means for adjusting the channel to change the contour of the blade, and mechanism for moving the sides of the channel closer together to grasp the blade and afford it lateral support.

3. An adjustable die including a channel for supporting a flexible cutter blade, said channel extending for a substantial portion of the length of the cut and being formed on one side by clamping plates which are movable to change the contour of the channel, and on the other side by flexible clamping means which take the contour determined by said clamping plates when holding a blade against the clamping plates, and means for moving said flexible clamping means toward the clamping plates to grasp a blade and afford it lateral support.

4. In an adjustable die, a clamping plate for determining the contour of a flexible cutter blade, a spring extending for a substantial distance along one face of the clamping plate, and means holding the spring in position to clamp a cutter blade between the spring and said face of the clamping plate.

5. An adjustable die including in combination, clamping plates which are relatively movable to change the contour of a flexible blade, a supporting plate on which the lower edge of the blade rests, a spring forming with the supporting plate and clamping plates, a channel for the flexible blade, and releasable means for urging the spring toward the clamping plates to cause the side walls of the channel to embrace and laterally support the cutting blade.

6. In an adjustable die, a support for a flexible cutting blade, plates for determining the outline of the flexible blade, two springs in position to clamp different portions of the blade against said plates, and common means for moving the springs against the blade including a member for equalizing the pressure of the springs.

7. An adjustable die for cutting vamps or other elements of shoe uppers, including a cutter, means for changing the form of the cutter to the contours of different size graded vamps or other elements, and a single operating member for actuating the form changing means.

8. Apparatus for cutting vamps or other elements of shoe uppers, comprising a flexible cutting blade, blade supporting means including devices for holding the blade to the outline of the edge to be cut, and mechanism for shifting said devices to bend the flexible blade to different contours corresponding to the outlines of different size graded vamps or other elements.

9. A vamp pinking apparatus comprising a flexible blade corrugated in accordance with the size of the pinking to be produced, means holding the pinking blade to the outline of the vamp edge, and mechanism for shifting the holding means to change the shape of the pinking blade to that of a different size vamp throat.

10. In or for an adjustable pinking die in which the blade is bent and the points of flexure changed when the die is adjusted, a blade formed of hard, ribbon stock with corrugations which shape the blade to cut a pinked edge, said corrugations extending across the full height of the blade to increase its flexibility so that any portion of the length of the blade can be alternately bent to a sharp curve and straightened without

deterioration or breakage of the metal of the blade.

11. A pinking blade consisting of a strip of metal sharpened on one edge and corrugated throughout its height and so thin and flexible as to conform readily to curves of short radii and to require substantially full lateral support to hold any imposed conformation.

12. A pinking blade comprising a metal strip of zig-zag form with the corrugations pointed at both sides of the strip and extending throughout the height of the strip to provide a flexible blade which conforms to straight lines, or long or short radius curves.

13. A pinking blade comprising a steel strip, of ribbon thickness and cutting hardness, having corrugations shaped to cut a pinked edge and extending for the full height of the blade so that the blade can bend around short radius curves without deterioration or breaking of the hard steel.

14. A pinking blade formed of ribbon stock and having corrugations which extend for the full height of the blade to give said blade a wavy cutting edge and to increase the flexibility of the blade so that it can be bent around sharp curves.

15. A blade for cutting a series of points along the edge of a piece of leather, cloth, or the like, said blade comprising a metal strip having a thickness of .005-.015 inch and at least one of its long edges sharpened, the blade being corrugated throughout its length with the corrugations pointed and extending the full height of the blade, and the metal of said blade being flexible to such degree that the blade may be bent around turns of short radius or abrupt angles up to ninety degrees.

16. An adjustable vamp-pinking die including means for clasping the mid-portion of a flexible pinking blade, supporting means on which the blade rests on either side of its mid-portion, releasable clamping means for holding the blade to the contour of a vamp edge, and mechanism for moving the clamping means, when released, to change the contour of the flexible blade to conform to vamps having wider and deeper throats, said flexible blade being adapted to slide in the clamping means while said clamping means are being moved to adjust the die.

17. In a vamp pinking die, an adjustable holder for a flexible pinking blade, said holder including several plates having faces so shaped and in such relation that a flexible blade clamped against said plates is held to the conformation of a vamp edge, and means for shifting the positions of the plates to conform the blade to a vamp of larger size having a throat which is both wider and deeper.

18. Apparatus for pinking the elements of shoe uppers comprising an adjustable holder for a flexible pinking blade, said holder including several clamping plates for contact with the same side of the blade, means for holding the blade against the clamping plates to give said blade the conformation of the blade-contacting faces of said clamping plates, said plates being shaped to give the blade a conformation with a substantially straight line joining two curves, and means for shifting the relative position of certain of the plates in the direction of the straight line portion of the blade to increase the length of said straight line when adjusting the holder for pinking elements of larger size.

19. In an adjustable die, a holder for a flexible blade including clamping means for holding the blade to a desired conformation, mechanism for shifting the clamping means to adjust the conformation of the blade, a handle for operating the shifting mechanism, and another handle for operating the clamping means, the clamping handle being located in position to interfere with the operation of the adjusting handle when the blade is clamped.

20. Vamp pinking apparatus comprising a base, two supporting plates movable sideways toward and from one another, a flexible pinking blade resting on said supporting plates, clamping plates on the supporting plates for holding the blade to the contour of the vamp edge to be pinked, said clamping plates including two end clamping plates, one of which is movable as a unit with each of the supporting plates, and two center clamping plates, each of which has a straight edge extending along one of the end clamping plates, means for causing the center clamping plates to move toward and from one another with the supporting plates so as to maintain said straight edges of the center clamping plates adjacent their end clamping plates, a clamp gripping the mid-portion of the flexible blade, mechanism for causing said clamp to move at right angles to the direction of movement of the supporting plates, said mechanism including means for causing the center plates to move with the clamp but in directions parallel to said straight edges at the same time that said center plates are moving with the supporting plates, springs contacting with the flexible blade throughout the greater portion of its length and holding it in firm contact with the clamping plates to afford lateral support to the blade, and means for releasing the pressure of said springs when the clamping plates are to be shifted to change the contour of the blade.

MERLE E. HALSTEAD.
